UNITED STATES PATENT OFFICE.

CLIFFORD M. HICKMAN, OF NEWARK, NEW JERSEY.

DESIGN FOR A LIGHTING FIXTURE.

Application filed November 12, 1924. Serial No. 11,363. Term of patent 14 years.

To all whom it may concern:

Be it known that I, CLIFFORD M. HICKMAN, a citizen of the United States, residing at Newark, in the county of Essex and State of New Jersey, have invented a new, original, and ornamental Design for a Lighting Fixture, of which the following is a specification, reference being had to the accompanying drawing, forming part thereof.

Fig. 2 is a bottom plan view thereof.

I claim:

The ornamental design for a lighting fixture, as shown.

CLIFFORD M. HICKMAN.
